United States Patent Office.

THOMAS DOLAN, OF PHILADELPHIA, PENNSYLVANIA.

Design No. 4,301, dated August 23, 1870.

DESIGN FOR A "PERSIAN CLOAK."

The Schedule referred to in these Letters Patent and making part of the same.

To all whom it may concern:

Be it known that I, THOMAS DOLAN, of the city of Philadelphia, in the State of Pennsylvania, have invented a new and original Design for a "Persian Cloak;" and I do hereby declare the following to be an exact description thereof, reference being had to the accompanying drawing, which forms a part of this specification.

To produce a "Persian cloak" shaped according to my design, I take a rectangular piece of goods, slit it a short distance lengthwise, as shown at A B, fig. 1, and then plait the part immediately below the slit to form a panier, as at C, fig. 2.

The garment is then doubled and cut down the middle from the top to the slit A B, as shown at D E, fig. 3, and tacked together at the two points F and G, and stitched or basted on the lines F H, G I, so as to present the appearance shown in fig. 4.

Each of the flaps K L is now formed into half a hood-piece by folding them over till the edges M N M O coincide with the middle line M P.

The flaps Q are then turned over or cut off, as shown in fig. 5, and the hood-piece K L is plaited into the form of a hood, shown in fig. 6.

What I claim as my invention, and desire to secure by Letters Patent of the United States, is—

The design or configuration of a "Persian cloak," produced by slitting it lengthwise, plaiting the lower part into a panier, cutting the upper part down the middle, stitching it together to form a hood-piece, and shaping the same into the form of a hood, as shown and described.

THOMAS DOLAN.
